(57) **CLAIM**

The ornamental design for a headphone, as shown and
described.

DESCRIPTION

FIG. 1 is a perspective view of a headphone showing our
new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines illustrating portions of the headphone form
no part of the claimed design. The dot-dash broken lines
defining boundaries of the claimed design form no part of
the claimed design.

1 Claim, 7 Drawing Sheets
